UNITED STATES PATENT OFFICE.

JOSEPH SCHWEGLER, OF BUFFALO, NEW YORK.

LIFTING-JACK.

SPECIFICATION forming part of Letters Patent No. 278,280, dated May 22, 1883.

Application filed April 18, 1882. (No model.)

To all whom it may concern:

Be it known that I, JOSEPH SCHWEGLER, of the city of Buffalo, in the county of Erie and State of New York, have invented a new and useful Improvement in Lifting-Jacks, of which the following is a specification.

This invention relates to an improvement in that class of lifting-jacks which are provided with a rack-bar upon which the load is supported, and which is raised by a gear-wheel engaging with said rack-bar and actuated by a hand-crank.

The object of my invention is to construct a lifting-jack of this character, whereby heavy loads can be raised with little effort, and in which the rack-bar can be readily lowered and arrested at any desired point.

My invention consists of the peculiar construction of the lifting-jack, which will be hereinafter fully set forth, and pointed out in the claims.

In the accompanying drawings, Figure 1 is a side elevation, and Fig. 2 a front elevation, of my improved lifting-jack. Fig. 3 is a vertical section of the same in line *x x*, Fig. 6. Fig. 4 is a vertical section of the upper portion of the jack in line *y y*, Fig. 6. Fig. 5 is a vertical section at right angles to Fig. 4. Fig. 6 is a horizontal section in line *z z*, Fig. 1. Fig. 7 is a top plan view.

Like letters of reference refer to like parts in the several figures.

A represents the upright frame of the lifting-jack, and *B* the vertical rack-bar, arranged to slide in a groove on the rear side of the frame *A*, and provided with a head, *b*, and a claw, *b'*, at its lower end, in the usual manner.

c represents a pinion which engages with the teeth of the rack-bar *B*, and which is mounted on or formed with a horizontal shaft, *d*, which is journaled in suitable bearings, *d'*, secured to the side walls of the frame *A*.

E represents a spirally-toothed wheel secured to the shaft *d*, and *F* is an endless screw engaging with the wheel *E*, and secured to or formed with a horizontal shaft, *f*, arranged above the wheel *E*, and at right angles to the shaft *d* of the wheel *E*. The shaft *f* turns in bearings which are formed in the ends of two levers, *G G'*, pivoted to the front and rear walls of the case *A* at *g* and *g'*, respectively. The opposite ends of the levers *G G'* are at-

tached to a cross-head, *H*, in such manner that by raising and lowering the latter the ends of the levers *G G'* attached to the cross-head are raised and lowered, and the opposite ends of the levers *G G'*, in which the screw-shaft *f* is journaled, are correspondingly lowered or raised, so that by lowering the cross-head *H* the shaft *f* is raised, whereby the endless screw *F*, mounted on said shaft, is disengaged from the screw-wheel *E*, while by a reverse movement of the cross-head the shaft *f* and its screw *F* are lowered and the latter caused to engage with the wheel *E*.

I represents a ratchet-wheel secured to the shaft *f*, and *i* is a pawl pivoted to the frame *A*, and engaging with the ratchet-wheel *I*, to prevent a retrograde movement of the shaft *f* in a well-known manner. *J* is a hand-crank secured to the outer end of the shaft *f* for rotating the same.

K is an eccentric pivoted to the side wall of the frame *A*, and engaging in a slot, *k*, formed in the cross-head *H*, so that by turning the eccentric *K* on its pivot the cross-head *H* is raised or lowered.

L is an arm formed on the eccentric *K*, and *l* is a handle pivoted to the arm *L* and pressed outward by a spring, *l'*, interposed between the handle *l* and the arm *L*.

M represents a catch secured to the frame *A*, and provided with a notch, *m*, into which the handle *l* is pressed by the spring *l'* when in an upright position, thereby locking the arm *L* and eccentric *K* in this position, in which the cross-head *H* holds the screw *F* in engagement with the wheel *E*. When the parts are in this position, as represented in Figs. 1, 2, 3, and 5, the rack-bar *B* is raised by turning the crank *J* in the direction indicated by the arrow in Fig. 2. If it is desired to lower the rack-bar *B*, the pawl *i* is disengaged from the wheel *I* and the arm *L* released by pushing the handle *l* out of the notch *m*. The eccentric *K* is then turned down, whereby the cross-head *H* is lowered and the shaft *f* and screw *F* are raised, thereby disconnecting the wheel *E* and rack-bar *B* from the worm-wheel and permitting the rack-bar to descend by its own weight. If it is desired to arrest the downward movement of the rack-bar before it reaches its lowest position, this is easily accomplished by returning the eccentric to its upper position, where-

by the screw F is brought into engagement with the wheel E, and the movement of the latter and of the rack-bar are instantaneously arrested. The screw F exerts considerable power upon the gear-rack by the intermediate gear-wheels, thereby enabling heavy loads to be raised by this lifting-jack; and this power may be further increased by placing a gear-wheel on the screw-shaft and applying the power to this gear-wheel by an endless screw engaging therewith.

I claim as my invention—

1. The combination, with the rack-bar B, of the pinion c, wheel E, actuating-screw F, shaft

f, levers G G', cross-head H, and mechanism, substantially as described, whereby the cross-head can be raised or lowered at desire, substantially as set forth.

2. The combination, with the rack-bar B, of the pinion c, wheel E, screw F, shaft f, levers G G', cross-head H, eccentric K, provided with an arm, L, and spring-catch M, substantially as set forth.

JOS. SCHWEGLER.
